UNITED STATES PATENT OFFICE.

CARL BJORNSON, EMIL BJORNSON, AND SIGFRED BJORNSON, OF BENTLEY, ALBERTA, CANADA; SAID SIGFRED BJORNSON ASSIGNOR TO JOSEPH EMMANUEL ADAMS, OF BENTLEY, CANADA.

WRENCH.

Application filed June 23, 1923. Serial No. 647,412.

This invention relates to an improved wrench, the general object of the invention being to provide means whereby the movable jaw can be easily and quickly adjusted by pressure on a spring controlled dog so that it is not necessary to actuate a screw member.

Another object of the invention is to make the wrench self-locking and to so form the parts that it can be used in close quarters.

This invention also consists in certain other features of construction and in the combination and arrangement of the several parts, to be hereinafter fully described, illustrated in the accompanying drawings and specifically pointed out in the appended claim.

In describing our invention in detail, reference will be had to the accompanying drawings wherein like characters denote like or corresponding parts throughout the several views, and in which:—

Figure 1 is a side elevation of my improved wrench;

Figure 2 is a similar view, the parts being broken away and illustrated in cross section;

Figure 3 is a perspective view of the pivoted casing and

Figure 4 is a perspective view of the pivoted dog.

In these views 1 indicates a handle which has a stationary jaw 2 formed at its end, the jaw part being extended above the handle and recessed, as at 3, for receiving the rounded end of a dog 4 so that the dog is movably supported in the recess. A casing 5' of U-shaped form is pivotally connected with the handle 1 by a single fastener 5'' so that it can rock and thus provide rocking movement of the movable jaw 6, the stem of which is slidable through the casing 5' and rests upon the lateral extension 6' of the stationary jaw. The rear end of the stem of the movable jaw has a projection 7 which slides on the upper edge of the handle and it also has ratchet teeth 8 in its lower edge which are engaged by the

dog, a spring 9 holding the dog in engagement with the teeth.

A button 10 is pivoted to the dog and extends through a slot 11 in one side of the casing so that by pushing on said button the wrench will be moved out of engagement with the teeth so that said jaw may be adjusted. As soon as pressure is released from the button the spring will force the wrench into engagement with one of the teeth on the jaw and thus push said body in an adjusted position.

To operate the wrench the handle is held with the jaw directly downwardly and then the release button is pressed so as to move the dog into inoperative position and then the movable jaw will drop to its wide open position. To release the wrench from a nut or other object the button is pressed upon and then the wrench can be moved off the object.

From the above it will be seen that we have produced a simple and effective wrench which can be easily and quickly placed in engagement with an object and just as easily disengaged from said object.

It is thought from the foregoing description that the advantages and novel features of the invention will be readily apparent.

We desire it to be understood that we may make changes in the construction and in the combination and arrangement of the several parts, provided that such changes fall within the scope of the appended claim.

What we claim is:—

A wrench of the class described comprising a handle having a stationary jaw, one edge of which extends laterally beyond one edge of the handle, a U-shaped casing having its side arranged against the sides of the handle for free swinging movement and pivotally connected with the handle in the rear of the stationary jaw, a movable jaw having its shank passing through the casing with one edge of the shank sliding on the extended edge of the stationary jaw, a projection on the inner end of the shank sliding on the edge of the handle in the rear

of the extended portion of the stationary jaw, teeth on the lower end of the shank, an arcuate recess in the rear face of the extended portion of the stationary jaw, a dog 5 in the casing having one end rockably mounted in said recess and its other end adapted to engage the teeth, a button connected with the dog and passing through

an elongated opening in the casing and a spring carried by the handle for normally 10 holding it in engagement with the teeth.

In testimony whereof we affix our signatures.

CARL BJORNSON.
EMIL BJORNSON.
SIGFRED BJORNSON.
